US0D1102854S

(12) **United States Design Patent** (10) **Patent No.:** **US D1,102,854 S**
(45) **Date of Patent:** **** Nov. 25, 2025**

(54) **SET OF HINGE WRENCHES**

(71) Applicant: **Shangrao Wobei Trading Co., Ltd,**
Shangrao (CN)

(72) Inventor: **Sisi Li**, Shangrao (CN)

(73) Assignee: **Shangrao Wobei Trading Co., Ltd,**
Shangrao (CN)

(**) Term: **15 Years**

(21) Appl. No.: **29/995,655**

(22) Filed: **Mar. 27, 2025**

(51) LOC (15) Cl. **08-05**

(52) U.S. Cl.

USPC **D8/21**

(58) **Field of Classification Search**

USPC D8/14, 21, 88, 107

CPC E04F 21/0015; B25B 13/5083

See application file for complete search history.
